DESIGN FOR A BROOCH OR SIMILAR ARTICLE

Elsa Maria Kafka, New York, N. Y.

Application July 18, 1940, Serial No. 93,778

Term of patent 3½ years

To all whom it may concern:

Be it known that I, Elsa Maria Kafka, a citizen of Austria, residing at New York, in the county of New York and State of New York, have invented a new, original, and ornamental Design for a Brooch, or Similar Article, of which the following is a specification, reference being had to the accompanying drawing, forming part thereof.

In the drawing:

Fig. 1 is a front elevational view of a brooch or similar article showing my new design; and
Fig. 2 is a perspective view thereof.

I claim:

The ornamental design for a brooch or similar article, as shown.

ELSA MARIA KAFKA.
